US00D536108S

(12) **United States Design Patent** (10) Patent No.: **US D536,108 S**
Adams et al. (45) Date of Patent: ** Jan. 30, 2007

(54) **FLAME-SHAPED WICK CLIP**

(75) Inventors: **Mary Beth Adams**, Antioch, IL (US);
Chris A. Kubicek, East Troy, WI (US);
Cory J. Nelson, Racine, WI (US);
Romuald Marie, Paris (FR); **Elie Papiernik**, Paris (FR)

(73) Assignee: **S.C. Johnson & Son, Inc.**, Racine, WI (US)

(**) Term: **14 Years**

(21) Appl. No.: **29/212,973**

(22) Filed: **Sep. 10, 2004**

(51) LOC (8) Cl. **26-04**

(52) U.S. Cl. **D26/7**

(58) Field of Classification Search **D26/6, D26/7; 431/298, 299, 301, 302**

See application file for complete search history.

(57) **CLAIM**

The ornamental design for a flame-shaped wick clip, as shown and described.

DESCRIPTION

FIG. 1 is an isometric view of a flame-shaped wick clip according to the present invention;
FIG. 2 is a front elevational view thereof;
FIG. 3 is a first side elevational view thereof;
FIG. 4 is a second side elevational view thereof;
FIG. 5 is a plan view thereof; and,
FIG. 6 is a bottom plan view thereof.

UNITED STATES PATENT AND TRADEMARK OFFICE
CERTIFICATE OF CORRECTION

PATENT NO. : Des. 536,108 S
APPLICATION NO. : 29/212973
DATED : January 30, 2007
INVENTOR(S) : Mary Beth Adams et al.

Page 1 of 1

It is certified that error appears in the above-identified patent and that said Letters Patent is hereby corrected as shown below:

Title page, under item [57]

Description: line 6, replace “; and,” with ---

Description: line 7, delete “FIG. 6 is a bottom plan view thereof.”

Drawings: delete “FIG. 6” and drawing

Signed and Sealed this

Nineteenth Day of August, 2008

JON W. DUDAS
Director of the United States Patent and Trademark Office
